FEEDING MECHANISM FOR SHAKER OR
JIGGING CONVEYERSErnst R. Bergmann, Chicago, Ill., assignor to
Goodman Manufacturing Company, Chicago,
Ill., a corporation of IllinoisApplication January 27, 1938, Serial No. 187,145
Renewed April 29, 1939

17 Claims. (Cl. 198—220)

This invention relates to improvements in feeding mechanisms for shaker or jiggling conveyers of the type utilized for picking up and transporting loose material such as coal, rock, or the like.

More specifically, the present invention is an improvement in the general form of feeding devices disclosed in my prior application Serial No. 86,154, filed June 19, 1936, which is now Patent No. 2,154,060 and in a prior application Serial No. 103,825, filed by William W. Sloane on Oct. 3, 1936.

Among the objects of my invention is to provide a feeding device of a simpler construction adapted to automatically extend or retract an extensible trough section with respect to a reciprocating trough section by reciprocable movement of the conveyer due to resistance of the extensible trough section against the ground, which includes a more efficient arrangement of adjusting mechanism for changing the gripping action of the friction gripping devices and for compensating for wear of said devices.

Other objects of my invention will appear from time to time as the accompanying specification proceeds.

My invention may best be understood with reference to the accompanying drawings, in which:

Figure 1 is a detail fragmentary view in side elevation of the front end of a conveyer trough line having a feeding mechanism constructed in accordance with my invention associated therewith, with certain parts of the feeding mechanism shown in section;

Figure 2 is a detail plan view of the feeding mechanism shown in Figure 1 showing certain parts of the conveyer trough broken away, and showing certain parts of the feeding mechanism in horizontal section;

Figure 3 is a fragmentary view in side elevation of the feeding device shown in Figure 1 with certain parts broken away and shown in longitudinal section in order to more clearly illustrate certain details of my invention;

Figure 4 is an enlarged transverse sectional view taken through one of the clamping devices;

Figure 5 is a plan view of one of the clamping devices drawn to substantially the same scale as Figure 4;

Figure 6 is a transverse sectional view taken substantially along line 6—6 of Figure 3;

Figure 7 is a diagrammatic view in side elevation of the forward end of the pan line showing the feeding device positioned for retracting the

extensible trough section within the reciprocating trough section; and

Figures 8 and 9 are diagrammatic views in side elevation illustrating the positions of the feeding device for extending or retracting the extensible trough section.

In the embodiment of my invention illustrated in the drawings, the main elements thereof include a reciprocating trough section 10 connected to the forward end of a shaker conveyer trough line (not shown). An extensible trough section or pickup member 11 is adapted to be telescopically extended or retracted with respect to said reciprocating trough section and is provided with a forwardly projecting flared gathering shovel 12 adapted to rest on and slidably move along the ground.

The pickup member 11 is similar to that described in my aforementioned prior application, and is supported above the ground at its rearward end on a shoe 13 so that the entire weight of said trough section rests on the ground. The reciprocating trough section 10 is supported at its forward end for free reciprocable movement along said pickup member by means of two pairs of rollers 16, 16 adapted to ride along bearing plates 17, 17 extending laterally from the upper flanges of said pickup member and engage the undersurface thereof upon the tendency of said trough sections to be vertically displaced with respect to each other.

The bearing plates 17, 17 are adapted to be selectively engaged by gripping devices 18, 18 for effecting feeding movement of said pickup member. Each of said gripping devices includes a set of friction grip blocks 25 and 26 mounted in a carrier member 27. Said carrier members are each of a substantially C-shaped formation having the open portion thereof extending inwardly along the respective bearing plate 17. The construction and operation of each of said gripping devices is similar so a description of one will suffice for both.

The lower friction grip block 26 is mounted in the C-shaped carrier member 27 beneath the open portion thereof on a transversely disposed shaft 28 extending through said carrier member and herein shown as being a bolt having a nut on its end. The upper friction grip block 25 is likewise mounted between the sides of said C-shaped carrier member on a transversely extending shaft or bolt 29. Said bolt is mounted in vertical slots 30, 30 extending above the open portion of said carrier member to permit adjustment of said upper friction grip block.

The means for adjusting the upper grip block 25 to compensate for wear thereof includes a pair of pins 31, 31 mounted at their upper ends in a cross member 32. Said pins extend through suitable apertures formed in the upper side of the carrier member 27 and engage the bolt 29 on opposite sides of said friction grip block. The lower portions of the inner sides of said pins are cut away to accommodate the forked ends of a link 33 pivotally mounted on said bolt on opposite sides of said grip block (see Figure 4). The purpose of said link will be more clearly explained as this specification proceeds. A machine screw 34 is mounted in the cross member 32 at its upper end and is threaded within said carrier member so that rotation thereof will adjustably move said cross member and pins with respect to said carrier member to provide for adjustment of the grip block 25 (see Figures 3, 4, and 5). Said machine screw is provided with a hexagonal portion 35 above the threaded portion thereof and is adapted to be held from rotation by means of a pin 36 adapted to be yieldably engaged with the sides of said hexagonal portion. Said pin, as herein shown, is mounted on the end of a leaf spring member 37 which is secured at its opposite end to said cross member. Said screw may be turned by means of a hand crank or wrench adapted to engage a squared head 38 disposed above said hexagonal head.

The link 33 extends rearwardly and downwardly from the bolt 29 and is pivotally mounted at its opposite end to the upper end of a bifurcated crank 40 on a pivotal pin 41. Said crank is in turn fixedly mounted on a transverse shaft 43 which is mounted in a forwardly extending forked bracket 44. Said bracket is pivotally connected to the lower forward portion of the bracket member 21 adjacent one side thereof by means of a pivotal pin 45.

The lower end of the carrier member 27 is connected to the forward end of the forked bracket 44 by means of a yieldable linkage arrangement which includes an eye bolt 46 threaded for a portion of its length and slidably mounted in an apertured boss 47, projecting forwardly from said bracket, for yieldable movement with respect thereto in a longitudinal direction. The eye of said bolt is pivotally connected to the lower end of the carrier member 27 on a pivotal pin 49 and the head of said eye bolt abuts the inside of said bracket. A compression spring 50 encircles said bolt and apertured boss and is interposed between the forward end of said bracket and a flanged sleeve 51. Said sleeve abuts a nut 53 threaded on said shaft to provide for adjustment of said spring.

Thus, when said pickup member is being extended with respect to said reciprocating trough section as shown by broken lines in Figure 8 and the forward end of the shovel engages an obstruction, the eye bolt 46 will yieldably move inwardly with respect to said bracket which will cause the carrier member to tend to move to a vertical position and move the associated grip blocks to a disengaged position with respect to the bearing plate 17.

The friction grip blocks 25 and 26 and carrier member 27 are maintained in a position for engaging the bearing plate 17 by means of a spring link 54 which engages the free end of a crank 55. Said crank is secured to the outer end of the transverse shaft 43 to move therewith. Said spring link includes a shaft 56 threaded for a portion of its length and secured at its lower end

to a member 57. Said member is pivotally connected to the end of the crank 55 by means of a pivotal pin 58 (see Figures 1 and 2). The opposite end of said shaft is slidably mounted in a member 59 which is pivotally mounted in a projecting end 60 of the bracket 44. A spring 61 encircles said shaft and is interposed between a nut 62 threaded on said shaft (for adjusting the compressive force of said spring) and the member 59. Said crank thus reacts against said spring link and said link tends to hold the carrier member in a position so that the grip blocks 25 and 26 will engage the bearing plate 17 upon the proper stroke of the conveyer.

Positioning of the carrier member 27 for feeding the extensible trough section in either a forward or return direction with respect to the reciprocating trough section is effected by means of a hand crank 63 mounted on the end of a transverse shaft 64 which extends transversely beneath the extensible trough section 11 and is mounted in the brackets 44, 44 adjacent its ends in a manner which will hereinafter more clearly appear. A crank 65 is mounted on and secured to the shaft 64 between the furcations of the bracket 44. Said crank in turn is connected to the crank 40 by means of a link 66, which is pivotally connected to said first mentioned crank by means of a pin 67 and which is pivotally connected to said second mentioned crank by means of the pin 41.

When the hand cranks 63 are in the position shown by broken lines in Figure 8 and the carrier member 27 is inclined in a rearward direction, the blocks 25 and 26 will be engaged with the bearing plates 17, 17 upon the forward stroke of the conveyer. This gripping action is attained by movement of the carrier member 27 about the axis of the bolt 29, effected through forward movement of the bracket 44 and eye bolt 46 through the spring 50 in a direction to clamp said grip blocks on said bearing plates. Upon the return stroke of the conveyer frictional resistance of the trough section 11 against the ground will hold said trough section from movement with respect to the ground to an extent sufficient to cause the carrier members 27, 27 to pivot in a counterclockwise direction about the axes of the bolts 29, 29, aided by return movement of the eye bolts 46, 46, and disengage said grip blocks from the bearing plates 17, 17. At the same time the spring links 54, 54 will be exerting pressure against the cranks 55, 55 to move said grip blocks to an engaged position with respect to said bearing plates as soon as a return stroke of the conveyer has been completed.

When either one of the hand cranks 63 is moved to the position shown in Figure 7, the parts are positioned for retracting the extensible trough section within the conveyer trough section. When in this position the carrier members 27, 27 will be pivoted about the axes of the bolts 29, 29 by the brackets 44, 44, compression springs 50, 50, and eye bolts 46, 46, which will engage the grip blocks 25 and 26 with said extensible trough section upon the return stroke of the conveyer, and tend to move said grip blocks to a released position with respect to said extensible trough section upon the forward stroke of the conveyer.

The grip blocks 25 and 26 are locked in an engaged position with respect to the bearing plates 17, 17 or locking the extensible trough with the reciprocating trough section when the hand crank 63 is pivoted in a clockwise direction against the

spring 58 until the crank 65 is in a position past dead center, as is shown in Figure 9.

The novel means for adjusting the gripping force of the grip blocks 25 and 26, and for compensating for wear of said blocks and the pins and links in the feeding mechanism is as follows:

The shaft 64 is mounted adjacent its ends in eccentric sleeves 68, 69. Each sleeve is mounted in the outer side of the forked bracket 44 for pivotal movement with respect thereto so that turning movement thereof will change the position of the shaft 64 and cranks 65 and 48 with respect to said bracket for increasing or decreasing the inclination of the carrier member 27 with respect to the bearing plates 17, 17, when positioned for either extending or retracting the extensible trough section. A flange 69 on the outer end of said eccentric sleeve abuts the outer side of said forked bracket and is provided with a plurality of apertures 70, 70 which are adapted to register with corresponding apertures 71, 71 provided in the outer side of said forked bracket. A plurality of nuts having bolts thereon and indicated by reference character 72 are adapted to register for engagement with said apertures and said sleeve and hold said sleeve in fixed relation with respect to said bracket.

When it is desired to change the force with which the grip blocks 25 and 26 engage the bearing plates 17, 17, to give said grip blocks a greater gripping pressure to compensate for an ascending grade, or a lesser gripping pressure when the feeding device is arranged down grade or along the level, or to take care of wear of said grip blocks and the links and pins of the feeding device, the bolts 72 are removed from the flange 69 and the eccentric sleeve 68 is turned in the desired direction to incline the carrier member 27 at a greater angle with respect to the vertical to obtain a greater gripping force, or at a lesser angle to decrease the gripping action of said grip blocks. Figure 1 shows this sleeve in one extreme position of adjustment and Figure 3 shows it in another extreme position of adjustment. An indicating lug 74 projects outwardly from the flange of each of said eccentric sleeves to form a means for indicating the position of adjustment of said sleeve so that each sleeve on each side of the conveyer may be in the same position of adjustment to enable a uniform gripping pressure to be attained by each set of grip blocks.

It will be seen from the foregoing that a new and improved form of automatic feeding mechanism for a shaker conveyer has been provided which is of a simplified construction and which includes a novel arrangement of links and levers for effecting engagement or disengagement of the gripping devices of the extensible trough section and which also includes a novel and efficient form of adjusting means to enable the gripping force of said gripping devices to be uniformly adjusted in a simplified manner.

While I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

I claim as my invention:

1. In a feeding device for shaker conveyers, a reciprocating trough section, an extensible trough section, means for extending or retract-

ing said extensible trough section with respect to said reciprocating trough section including a carrier member, a pair of friction grip blocks mounted therein, a bracket pivotally connected to the forward end of said reciprocating trough section, a link mounted in said bracket for yieldable movement with respect thereto in a longitudinal direction and a pivotal connection between said link and one end of said carrier member, a crank pivotally mounted in said bracket and a connection between said crank and the other end of said carrier member, means for positioning said carrier member to extend or retract said extensible trough section including another crank pivotally mounted in said bracket and a connection between said crank and said first mentioned crank, and other means for adjusting said carrier member to change the gripping force of said grip blocks including an eccentric member mounted in said bracket and forming a support for said second mentioned crank.

2. In a feeding device for shaker conveyers, a reciprocating trough section, an extensible trough section, means for extending or retracting said extensible trough section with respect to said reciprocating trough section including a carrier member, a pair of friction grip blocks mounted therein, a bracket pivotally connected to the forward end of said reciprocating trough section, a link mounted in said bracket for yieldable movement with respect thereto in a longitudinal direction and a pivotal connection between said link and one end of said carrier member, a crank pivotally mounted in said bracket and a connection between said crank and the other end of said carrier member, means for positioning said carrier member to extend or retract said extensible trough section including another crank pivotally mounted in said bracket and a connection between said crank and said first mentioned crank, and other means for adjusting said carrier member to change the gripping force of said grip blocks including an eccentric member mounted in said bracket and forming a support for said second mentioned crank, and means permitting said member to be rotatably moved to vary the angular position of said crank with respect to said bracket, said means also forming a means for holding said member from rotation.

3. In a feeding device for shaker conveyers, a reciprocating trough section, an extensible trough section, means for extending or retracting said extensible trough section with respect to said reciprocating trough section including a carrier member, a pair of friction grip blocks mounted therein, a bracket pivotally connected to the forward end of said reciprocating trough section, a link mounted in said bracket for yieldable movement with respect thereto in a longitudinal direction and a pivotal connection between said link and the lower end of said carrier member, a crank pivotally mounted in said bracket and a connection between said crank and the upper end of said carrier member, means for adjusting the position of said carrier member for extending or retracting the extensible trough section including another crank pivotally mounted in said bracket and a connection between said crank and said first mentioned crank, and other means for adjusting said carrier member and the gripping force of said grip blocks including an eccentric sleeve forming a support for said last mentioned crank.

4. In a feeding device for shaker conveyers,

a reciprocating trough section, an extensible trough section, means for extending or retracting said extensible trough section with respect to said reciprocating trough section including a carrier member, a pair of friction grip blocks mounted therein, a bracket pivotally connected to the forward end of said reciprocating trough section, a link mounted in said bracket for yieldable movement with respect thereto in a longitudinal direction and a pivotal connection between said link and the lower end of said carrier member, a crank pivotally mounted in said bracket and a connection between said crank and the upper end of said carrier member, means for adjusting the position of said carrier member for extending or retracting the extensible trough section including another crank pivotally mounted in said bracket and a connection between said crank and said first mentioned crank, and other means for adjusting said carrier member and the gripping force of said grip blocks including an eccentric sleeve forming a support for said last mentioned crank and means permitting said sleeve to be rotatably moved to vary the angular position of said crank with respect to said bracket, said means also forming a means for holding said support from rotation.

5. In a feeding device for shaker conveyors, a reciprocating trough section, an extensible trough section, means for extending or retracting said extensible trough section with respect to said reciprocating trough section including a carrier member on each side of said extensible trough section having friction grip blocks mounted therein, a bracket pivotally connected to the forward end of each side of said reciprocating trough section and projecting forwardly therefrom, a link mounted in each of said brackets for yieldable movement with respect thereto in a longitudinal direction, and pivotal connections between said links and the lower ends of said carrier members, a crank pivotally mounted in each of said brackets and connections between each of said cranks and the upper ends of said carrier members, means for positioning said carrier members to extend or retract the extensible trough section including a shaft mounted adjacent its ends in said brackets and extending beneath said extensible trough section, a pair of cranks mounted on said shaft, each of said cranks being adjacent one of said brackets, and links connecting said first mentioned cranks with said last mentioned cranks, and other means for adjusting the gripping force of said grip blocks including an eccentric sleeve mounted in each of said brackets and forming bearings for said shaft.

6. In a feeding device for shaker conveyors, a reciprocating trough section, an extensible trough section, means for extending or retracting said extensible trough section with respect to said reciprocating trough section including a carrier member on each side of said extensible trough section having friction grip blocks mounted therein, spaced brackets projecting forwardly from opposite sides of said reciprocating trough section and pivotally connected thereto, a link mounted in each of said brackets for yieldable movement with respect thereto in a longitudinal direction and pivotal connections between said links and one of the ends of said carrier members, a crank pivotally mounted in each of said brackets and connections between said cranks and the opposite ends of said carrier members, means for adjustably moving said carrier members to extend or retract the extensible trough

section including a shaft mounted adjacent its ends in said brackets and extending beneath said extensible trough section, a pair of cranks mounted on said shaft, each of said cranks being adjacent one of said brackets, connections between said first mentioned cranks and said last mentioned cranks, and other means for adjusting the gripping force of said grip blocks including an eccentric sleeve mounted in each of said brackets and forming bearings for said shaft, and means permitting said sleeves to be rotatably moved to vary the angular position of said cranks with respect to said brackets, said means also forming a means for holding said sleeves from rotation.

7. In a feeding device for shaker conveyors, an extensible trough section supported so that its entire weight rests on the ground independently of the rest of the conveyer, a reciprocating trough section mounted for free movement along said extensible trough section, means actuated by reciprocal movement of the conveyer due to resistance of said extensible trough section on the ground for automatically extending or retracting said extensible trough section with respect to said reciprocating trough section including friction gripping means and a carrier member forming a support therefor, a forwardly extending bracket pivotally connected to the forward end of said reciprocating trough section and a link mounted in said bracket for yieldable movement with respect thereto in a longitudinal direction, a pivotal connection between said link and one end of said carrier member, a link connected to the other end of said carrier member, a crank pivotally mounted in said bracket and having pivotal connection with said second mentioned link, another crank mounted coaxial with said first mentioned crank for movement therewith and a spring link engaging the end of said crank and forming a means against which said cranks react, a third crank spaced from said first two cranks and having connection with said first mentioned crank for positioning said carrier member to extend or retract the conveyer, and means for adjusting the position of said third crank with respect to said bracket and adjusting the gripping action of said gripping means including an eccentric sleeve within which said last mentioned crank is mounted.

8. A feeding device in accordance with claim 7 wherein means registering for engagement with the sleeve and bracket are provided for holding said sleeve in fixed relation with respect to said bracket or permitting said sleeve to be adjustably moved with respect to said bracket.

9. In a feeding device for shaker conveyors, an extensible trough section supported so that its entire weight rests on the ground independently of the rest of the conveyer, a reciprocating trough section mounted at its forward end for free movement along said extensible trough section, means actuated by reciprocal movement of the conveyer due to resistance of said extensible trough section on the ground for automatically extending or retracting said extensible trough section with respect to said reciprocating trough section including friction gripping devices and a carrier member mounted on each side of said extensible trough section in advance of said reciprocating trough section and forming supporting means for said friction gripping devices, means for connecting said carrier members with said reciprocating trough section including a forwardly extending bracket pivotally connected to each side

- of the forward end of said reciprocating trough section, connecting members mounted in said brackets for yieldable movement with respect thereto in a longitudinal direction, pivotal connections between said members and the lower ends of said carrier members, a crank pivotally mounted in each of said brackets and links connecting the upper ends of said carrier members with said cranks, another crank mounted coaxial with each of said first mentioned cranks and spring links engaging the ends of said cranks, means for positioning said carrier members to extend or retract the conveyer including a transverse shaft mounted adjacent its ends in said brackets, a third crank on said shaft adjacent each end thereof, a connection between each of said first and third mentioned cranks, and means for adjusting the position of said third mentioned cranks with respect to said brackets and adjusting the gripping action of said gripping means including an eccentric sleeve mounted in each of said brackets and forming bearings for said shaft.
10. A feeding device in accordance with claim 9 wherein means registering for engagement with the sleeves and brackets are provided for holding said sleeves from rotation or permitting adjustable movement thereof with respect to said brackets.
11. A feeder head for shaker conveyers including an extensible trough section, a carrier member mounted for rocking movement with respect to said extensible trough section, a pair of friction grip blocks mounted in said carrier member and adapted to grip said extensible trough section above and below a portion thereof upon certain strokes of the conveyer, means for positioning said carrier member to cause said grip blocks to extend or retract said extensible trough section at will including a crank arm, a connection from said crank arm to said carrier member, and means for adjusting the position of said carrier member with respect to said extensible trough section to change the gripping force of said grip blocks including an eccentric member mounted for adjustable movement about a transverse axis and forming a pivotal support for said crank arm.
12. A feeder head for shaker conveyers including an extensible trough section, a carrier member mounted for rocking movement with respect to said extensible trough section, a pair of friction grip blocks mounted in said carrier member and adapted to grip said extensible trough section above and below a portion thereof upon certain strokes of the conveyer, means for positioning said carrier member to cause said grip blocks to extend or retract said extensible trough section at will including a crank arm, a connection from said crank arm to said carrier member, means for adjusting the position of said carrier member with respect to said extensible trough section to change the gripping force of said grip blocks including an eccentric member mounted for adjustable movement about a transverse axis and forming a pivotal support for said crank arm, and means for permitting adjustable turning movement of said eccentric member, to vary the angular position of said crank arm, said means also forming a means for holding said eccentric member from rotation.
13. In a feeding device for shaker conveyers, a reciprocating trough section, an extensible trough section adapted to be nested therein, a carrier member having a pair of friction grip blocks mounted therein for extending or retracting said extensible trough section with respect to said reciprocating trough section, a bracket pivotally connected to said reciprocating trough section, operative connections from said bracket to said carrier member for engaging said grip blocks with said extensible trough section upon certain strokes of the conveyer, means for positioning said carrier member to cause said grip blocks to extend or retract said extensible trough section including a crank arm, a connection from said crank arm to said carrier member, and means for adjusting the angle of said carrier member with respect to said extensible trough section to change the gripping force of said grip blocks including an eccentric sleeve mounted in said bracket and forming a pivotal support for said crank arm.
14. In a feeding device for shaker conveyers, a reciprocating trough section, an extensible trough section adapted to be nested therein, a carrier member having a pair of friction grip blocks mounted therein for extending or retracting said extensible trough section with respect to said reciprocating trough section, a bracket having pivotal connection with said reciprocating trough section, operative connections from said bracket to said carrier member for engaging said grip blocks with said extensible trough section upon certain strokes of the conveyer, means for positioning said carrier member to cause said grip blocks to extend or retract said extensible trough section including a crank arm, a connection from said crank arm to said carrier member, means for adjusting the angle of said carrier member with respect to said extensible trough section to change the gripping force of said grip blocks including an eccentric sleeve mounted in said bracket and forming a pivotal support for said crank arm, and means permitting said sleeve to be rotatably moved to vary the angular position of said crank arm with respect to said bracket, said means also forming a means for holding said sleeve from rotation.
15. A carrier member for feeding devices for shaker conveyers including a frame having an open central portion, a pair of friction grip blocks, a pivotal pin for mounting each of said grip blocks in said frame above and below the open portion thereof, said grip blocks being adapted to engage a shaker conveyer trough section above and below a portion thereof upon certain strokes of the conveyer, and means for adjustably moving said upper grip block towards said lower grip block and holding it in adjustment with respect to said lower grip block including a pair of pins slidably mounted in said frame and having engagement with said pin which supports said upper grip block, on opposite sides of said grip block, a member connecting said pins together, and a threaded member having engagement with said member and frame for moving said member and upper grip block towards said lower grip block upon turning movement of said threaded member.
16. A carrier member for feeding devices for shaker conveyers including a frame having an open central portion, a pair of friction grip blocks mounted in said frame, a pivotal pin for mounting each of said grip blocks in said frame above and below the open portion thereof, said grip blocks being adapted to engage a shaker conveyer trough section above and below a portion thereof upon certain strokes of the conveyer, and means for adjustably moving said upper grip block

block towards said lower grip block and holding it in adjustment with respect to said lower grip block including a pair of parallel spaced pins slidably mounted in said frame and having engagement with said pin which supports said upper grip block, on opposite sides of said grip block, a member connecting said pins together, a threaded member having engagement with said member and frame for moving said pins towards said lower grip block upon turning movement of said threaded member, and means for selectively holding said threaded member from turning movement.

17. A carrier member for feeding devices for shaker conveyers including a frame having an open central portion, a pair of friction grip blocks mounted in said frame, a pivotal pin for mounting each of said grip blocks in said frame above and below the open portion thereof, said grip blocks being adapted to engage a shaker con-

veyer trough section above and below a portion thereof upon certain strokes of the conveyer, and means for adjustably moving said upper grip block towards said lower grip block and holding it in adjustment with respect to said lower grip block including a pair of parallel spaced pins slidably mounted in said frame and having engagement with said pin which supports said upper grip block, a member connecting said pins together, and a threaded member having engagement with said member and frame for moving said pins towards said lower grip block upon turning movement of said threaded member, said threaded member having an irregularly formed portion, and yieldable means adapted to have engagement with said irregularly formed portion for selectively holding said threaded member from rotation.

ERNST R. BERGMANN. 20
